(57) **CLAIM**

I claim the ornamental design for a vehicular cell phone charger, as shown and described.

DESCRIPTION

FIG. 1 is a front view of a vehicular cell phone charger;
 FIG. 2 is a back view of the claimed design.
 FIG. 3 is a left view thereof;
 FIG. 4 is a right view thereof;
 FIG. 5 is a top view thereof; and,
 FIG. 6 is a bottom view thereof.
